(57) **CLAIM**

The ornamental design for a cosmetics container, as shown and described.

DESCRIPTION

FIG. 1 is a front, right, top perspective view of a cosmetics container.

FIG. 2 is bottom perspective view of the cosmetics container of FIG. 1.

FIG. 3 is a front elevation view of the cosmetics container of FIG. 1.

FIG. 4 is a rear elevation view of the cosmetics container of FIG. 1.

FIG. 5 is a left side elevation view of the cosmetics container of FIG. 1.

FIG. 6 is a right side elevation view of the cosmetics container of FIG. 1.

FIG. 7 is a top plan view of the cosmetics container of FIG. 1; and,

FIG. 8 is a bottom plan view of the cosmetics container of FIG. 1.

The broken lines in FIGS. 2 and 8 illustrate portions of the cosmetics container that form no part of claimed design.

1 Claim, 4 Drawing Sheets
